(57) **CLAIM**

The ornamental design for an oral care device, as shown and described.

DESCRIPTION

FIG. 1 is a front perspective view of an oral care device; FIG. 2 is a front elevation view thereof; FIG. 3 is a back elevation view thereof; FIG. 4 is a left side elevation view thereof; FIG. 5 is a right side elevation view thereof; FIG. 6 is a top plan view thereof; FIG. 7 is a bottom plan view thereof; and, FIG. 8 is a perspective view of the oral care device, shown in a condition of use for clarity of disclosure.

The broken lines in the drawings depict portions of the oral care device that form no part of the claimed design. The broken lines showing a human head in FIG. 8 depict environmental structure that forms no part of the claimed design. All broken lines form no part of the claim.

The dash-dot-dot-dash broken lines in the drawings represent borders of unclaimed portions of the design and form no part of the claimed design. The oral care device shown with a symbolic break near its distal end. The appearance of any portion of the article between the break lines forms no part of the claimed design.
